CLAIM

The ornamental design for a powered stapler, as shown and described.

DESCRIPTION

FIG. 1 is a perspective view of the powered stapler showing our new design;

FIG. 2 is a top view thereof;

FIG. 3 is a side elevational view thereof (with the other side view being the mirror image);

FIG. 4 is an end elevational view thereof; and

FIG. 5 is the opposite end elevational view thereof.

FIG. 1.

FIG. 2.

FIG. 3.

FIG. 4.

FIG. 5.
